United States Patent Office

Des. 213,819
Patented Apr. 15, 1969

213,819

BRASSIERE

Charles M. Sachs, West Englewood, N.J., assignor to International Playtex Corporation, New York,
N.Y., a corporation of Delaware

Filed Dec. 7, 1966, Ser. No. 4,966

Term of patent 14 years

Int. Cl. D2—02

U.S. Cl. D2—24

FIG. 1 is a plan view of a brassiere showing my new design.

FIG. 2 is a plan view of a second embodiment of the design of FIG. 1.

I claim:

The ornamental design for a brassiere, as shown and described.
